UNITED STATES PATENT OFFICE

158,857

SPECTACLE FRAME OR SIMILAR ARTICLE

Irving Hirschman, Brooklyn, N. Y.

Application January 21, 1949, Serial No. 372

Term of patent 7 years

(Cl. D57—1)

To all whom it may concern:

Be it known that I, Irving Hirschman, a citizen of the United States, residing at Brooklyn, in the county of Kings and State of New York, have invented a new, original, and ornamental Design for a Spectacle Frame or Similar Article, of which the following is a specification, reference being had to the accompanying drawing, forming a part thereof.

Fig. 1 is a front elevational view of a spectacle frame or similar article, showing my new design.

Fig. 2 is a side view thereof.

Fig. 3 is a sectional view taken on line 3—3 of Fig. 2, but drawn to an enlarged scale.

Fig. 4 is a fragmentary view on an enlarged scale of the ornamentation as shown on the narrow bar on the side of the spectacle temple, the same being carried throughout the length of this bar and the identical pattern appearing on the bars on the front of the spectacle frame.

The essential features of my design for a spectacle frame reside in the parts shown in full

lines and consist of ornamenting the outer sides of the temples and the front immediately above the lens openings with narrow bars showing thereon the specific pattern of ornamentation as seen most clearly in Fig. 4, all as illustrated on the drawing.

I claim:

The ornamental design for a spectacle frame or similar article, substantially as shown and described.

IRVING HIRSCHMAN.
